[75] Inventor: **Charles J. DiPasquale**, Argyle, Tex.

Primary Examiner—Lisa P. Lichtenstein
Attorney, Agent, or Firm—Dennis T. Griggs

[73] Assignee: **Smartel, Inc.**, Carrollton, Tex.

[57] **CLAIM**

[**] Term: **14 Years**

The ornamental design for a combined ceiling fan and light
with balloon decoration, as shown and described.

[21] Appl. No.: **32,512**

DESCRIPTION

[22] Filed: **Dec. 20, 1994**

FIG. 1 is a side elevational view of a combined ceiling fan
and light with balloon decoration showing my new design,
the opposite and adjacent sides being mirror images of that
shown, and the broken line showing of mounting structure
being for illustrative purposes only and forming no part of
the claimed design;

FIG. 2 is a top plan view thereof;

FIG. 3 is a bottom plan view thereof; and,

FIG. 4 is a bottom perspective view thereof.
